UNITED STATES PATENT OFFICE.

JOHN KENDRICK AND JOSEPH H. KENDRICK, OF PROVIDENCE, RHODE ISLAND.

MACHINE FOR DRESSING WEAVER'S HARNESS.

Specification of Letters Patent No. 43,777, dated August 9, 1864.

To all whom it may concern:

Be it known that we, JOHN KENDRICK and JOSEPH H. KENDRICK, both of the city and county of Providence, in the State of Rhode Island, have invented certain new and useful Improvements in Machines for Dressing Weavers' Harnesses; and we do hereby declare that the following specification, taken in connection with the drawings making a part of the same, is a full, clear, and exact description thereof.

Figure 1, is a plan of the machine. Fig. 2, is an end view. Fig. 3, is a section in a plane, through the line A. B. Fig. 4, is a section in a plane through the line C. D.

Before a weaver's harness is fit to be introduced into a power loom it is necessary that all the fibers upon the outside of the twine of which it is made should be laid uniformly in one direction so that the surface will be perfectly smooth and not injure the warp of the cloth.

To accomplish this more perfectly than it has heretofore been done by hand labor is the object of our improvement.

The machine which is represented in the drawings consists of the following principal parts. First, a carriage upon which the harness is placed mounted on a frame on which it is strained so that the twines will be taut, and which carriage has a reciprocating movement upon a suitable track, imparted to it at intermittent periods, and second, one or more pairs of brushes made to revolve in the same direction between which the harness carriage is made to travel, and which brushes are made to alternately approach toward and recede from each other during determined periods, so that while the harness is traveling upon the carriage in one direction the brushes will be clear of it, but on the return movement they will close upon it and perform their office.

The mechanism in which this mode of operation is embraced is as follows:

A, A, is a strong rectangular frame upon which the several parts are mounted and should be of sufficient length to accommodate the largest size of harness. Motion is communicated from the pulley shaft B through the toothed wheels C, and D, to the cam shaft D', (Fig. 1.) This shaft carries two cams E and F, the former of which controls the movement of the brushes G, G', (Fig. 2) in their action upon the harness to

be dressed and the latter governs the movement of the harness carriage.

The harness carriage consists of a rectangular frame H, removable at pleasure (shown broken off in Fig. 1 and an end view 60 in Figs. 3 and 4) provided at convenient distances with hooks a, a, against which the shafts of the harness are placed. The carriage should be constructed in two parts one part being provided with slots and secured 65 to the other by clamp screws b, (Fig. 1) for the purpose of adjusting the same to harnesses of different widths and the portion which is not slotted should also be provided with a bar extending along the side upon 70 which are placed holding hooks and which bar is held in place by a spring c, so that after the shafts of the harness are hooked to the carriage the tension of the spring will cause the twines to be strained taut. 75

Upon the under side of the carriage is placed a projecting piece d (Fig. 4) provided with a notch which receives a pin d' secured to the arm I, near the upper end. To this arm which is pivoted at e to a cross 80 bar of the frame a vibrating motion is imparted by the cam F acting through the bell crank J the upper arm of which is connected with the arm I by means of the link K and which by means of a clamp f, as shown 85 can be adjusted to different positions upon the arm I, to vary the extent of its arc of vibration. It is obvious that as the shaft D' revolves the harness carriage will be made to travel forward and backward upon 90 a track made for the purpose, with the vibration of the arm I, and that its periods of rest and motion can always be fixed and determined by the shape of the actuating cam F.

G, G, are two cylindrical brushes revolving in the same direction (and additional pairs can be used if desired) which extend across the machine one being located directly above the other, and are fitted to turn in bearings upon each end which rest upon the levers L, L, (Fig. 2.) These levers whose fulcra are respectively at g and g', will alternately approach and recede from each other as the rocker arm M on the shaft M', with which the end of each lever, as 105 shown in Fig. 2, is connected, is vibrated and consequently the brushes G, G, will have a position relating to each other dependent upon the position of the rocker arm. The rocker shaft M' is worked for this pur- 110

pose by the arm N, (Fig. 3) which is operated by the cam E upon the shaft D', as shown, the action of which relatively to the movement of the harness carriage above described it is clear can be readily governed by the shape of the cam E, and its position upon its shaft.

The operation of the machine is as follows: The harness to be dressed is placed upon the carriage; the forward movement of the lever I carries the carriage with the harness between the brushes which are too far apart to act upon it. When the carriage has reached the extent of its movement and is about to return the brushes close upon the harness and as the carriage returns lays the fibers of the twines evenly and uniformly in one direction.

We do not limit ourselves to the precise construction of the several parts as described, but we mean to claim all mere formal variations of mechanism operating by equivalent means.

What we do claim as of our invention and desire to secure by Letters Patent is—

1. The method substantially as specified of dressing weavers harnesses by the combination of a reciprocating carriage H upon which the harness is strained, with brushes G, G, or their equivalents revolving in the same direction, between which the harness to be dressed is made to travel as herein described.

2. The mode of operation substantially as specified by means of which the revolving brushes G, G, or other equivalent instruments for dressing, the harnesses are made to have a motion relatively to each other and to the harness carriage so as to act upon the harness only during its movement in one direction as herein described.

JOHN KENDRICK.
